(57) **CLAIM**

The ornamental design for a luminaire, substantially as shown and described.

DESCRIPTION

FIG. 1 is a front perspective view of our luminaire.

FIG. 2 is a front side view of the luminaire.

FIG. 3 is a back side view of the luminaire.

FIG. 4 is a right end view of the luminaire.

FIG. 5 is a left end view of the luminaire.

FIG. 6 is a top view of the luminaire.

FIG. 7 is a bottom view of the luminaire.

FIG. 8 illustrates the profile of the lower surfaces of the luminaire of FIG. 1, as taken in any vertical plane perpendicular to the length of the luminaire; and,

FIG. 9 is an enlarged perspective view of one end of the luminaire.

The broken (dash) lines illustrate environmental features that form no part of the claimed design, such as cables from which the luminaire might be hung from a ceiling, or end caps that might be used with the luminaire design. The broken (dot-dash) lines indicate boundaries of the claimed design. For example, a broken (dot-dash) transverse line beyond which all lines are dashed indicates that the design may be employed in products of different lengths.

1 Claim, 5 Drawing Sheets
